CLAIM

The ornamental design for an organizer and storage case for office and school supplies, as shown and described.

DESCRIPTION

FIG. 1 is a top and side perspective view of an organizer and storage case for office and school supplies showing our design, with a hinge lid in an open position;

FIG. 2 is a top, front, and right side perspective view thereof with the left side constituting a mirror-image of the right side, shown with the lid in a closed position; and,

FIG. 3 is a bottom, rear, and right side perspective view thereof, shown with the lid in an open position.
